FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

INDUCTOR HELIX.

Application filed January 27, 1925. Serial No. 5,048.

My invention relates to inductors and particularly to inductors suitable for use with radio-frequency apparatus such as short wave radio signalling systems.

5 An object of my invention is to produce an inductor device in which the energy losses therein are a minimum.

Another object of my invention is to produce an inductor device adapted for the 10 ready dissipation of heat produced therein by energy losses.

Another object of my invention is to produce a compact glass insulated inductance device.

15 Another object of my invention is to produce a well-insulated low-loss inductance device particularly adapted for use in apparatus for generating alternating currents at frequencies above 1000 kilocycles.

20 Another object of my invention is to produce an inductance having a conductor ribbon mounted upon heat-resisting glass insulating means.

Another object of my invention is to produce 25 an inductance device capable of carrying large currents of high voltage at radio frequency.

In the prior construction of inductances adapted to cooperate with radio-frequency 30 generating apparatus numerous difficulties have been experienced.

It is well known that the energy losses produced by electrostatic and electromagnetic hysteresis effects increase very rapidly with 35 increase in frequency, for which reason difficulty has been anticipated in constructing inductances capable of handling large quantities of electrical energy at the high frequency corresponding to short electro-magnetic wave lengths. It has been found that, at frequencies of 1500 kilocycles or higher, much difficulty is experienced with the generation of heat in the associated parts of the structure.

It has been found that phenolic condensation product material, such as "micarta" has 45 such high electrostatic and electromagnetic losses that at the higher frequencies, a prohibitive amount of energy is wasted in them, causing an amount of heating which not infrequently damages the apparatus. This material, which is entirely satisfactory at medium and long wave lengths, is found very unsatisfactory at short wave lengths. Attempts to use wood as the supporting frame

work have encountered similar difficulties, 55 the presence of moisture in the wood causes it to have high di-electric and electromagnetic hysteresis losses that are troublesome.

Likewise, at these high frequencies, the "skin effect," which causes the maximum density of current flow to occur at the surface of the conductor and, in a helix, at the outer surface of the coil, causes the resistance losses to mount to a prohibitively high value, thereby generating undesirable large quantities 60 of heat in the inductance, which are removed only with difficulty and which likewise injure the insulating supports upon which it is mounted.

My invention provides a simple construction 70 which provides substantial reductions in the energy losses in a helix and which provides a construction much less affected by heat.

Other objects and structural details of my 75 invention will be apparent from the following description and the accompanying drawing, wherein:

Figure 1 is a view in end elevation of an embodiment of my invention,

Fig. 2 is a view in side elevation of my invention,

Fig. 3 is a view in side elevation of the insulator members of my invention, and

Fig. 4 is a view in end elevation of an embodiment of my invention adapted to cooperate 85 with apparatus using extremely short wave lengths.

Referring to Figs. 1 and 2, a set of annular rings 1, 2 and 3 have attached thereto a plurality of grooved cross-pieces 4. A pair of supporting members 5 are respectively attached to end rings 1 and 3. These members are preferably made of wood and before assembly are given a special treatment.

This treatment consists of a very careful drying in a heated evacuated chamber, thereby removing practically all moisture from the wood. The drying treatment is then preferably followed by an immersion in an 100 insulating gum applied under pressure, the gum being chosen to have the lowest possible di-electric and electromagnetic hysteresis losses.

Alternatively, the wood may be carefully 105 dried and the surface sealed with a suitable insulating covering. Such construction produces a minimum loss within its body from

di-electric and electromagnetic hysteresis and its open frame work construction permits free circulation of cooling air.

Upon the cross pieces 4 are mounted the insulating members 6 each preferably formed of pressed, heat-resisting glass, such as "pyrex" that are rectangular in shape and have a plurality of spaced projections upon one face. The face carrying the projections, preferably is slightly convex with rounded corners. The glass insulator pieces are preferably supported in the grooves in the cross-pieces 4. Upon insulating members 6 is wound a helical ribbon conductor 7, the opposite ends being attached to the glass insulating members by being looped thereabout and the end secured by a suitable bolt and binding post. The ribbon form of the conductor provides a larger surface on the outside of the helix for the flow of the currents forced there by the "skin effect," and thereby reduces the effective high-frequency resistance and the energy loss, and thereby the heat developed. Tension screws 8, shown in dotted lines in the drawing, are provided whereby pressure can be applied to one of the cross-pieces 4 and transmitted through an insulator 6 to draw the turns of helix 7 taut.

The insulator members 6 are preferably made in the form shown in Fig. 3, having relatively short sections capable of supporting a portion only of the turns of the helix. By this means, a better distribution is obtained of the pressure strains from the helix which is under tension.

In Fig. 4 is shown a second embodiment of my invention in which the annular rings 1 of the preceding figures are replaced by polygonal wooden supporting pieces 11 to which are attached lengthwise pieces 4 which are similarly treated with an insulating gum as above described. They are also of the same type of construction as are shown in Figs. 1 and 2. Upon cross pieces 4 are similarly supported insulating members 6 as in the preceding figures. A helix 7 is similarly wound upon the insulating members. This construction gives a relatively small helix, having the necessary small inductance for the generation of wave lengths of 50 to 100 meters, which is, at the same time, capable of carrying radio-frequency currents corresponding to energy inputs of 10 to 20 kilowatts. The first embodiment of my invention is adapted to carry currents corresponding to similar powers at wave lengths of 200 to 500 meters.

By the construction of the different embodiments of my invention, I have produced an inductor helix which is capable of carrying relatively large powers of electrical energy at extremely high frequencies and in which the energy losses are relatively small.

While I have shown but two embodiments

of my invention in the accompanying drawings, it is capable of various changes and modifications without departing from the spirit thereof, and it is desired, therefore, that only such limitations shall be imposed thereon as are indicated in the prior art or in the appended claims.

I claim as my invention:

1. An inductor device comprising a wooden frame, treated with an insulating moisture-excluding material, whereby dielectric and hysteresis losses therein are reduced, a plurality of heat-resisting vitreous insulating members supported thereby and having low dielectric and hysteresis loss properties, and a helical conductor thereon. 75

2. An inductor device comprising a conductive helix and means for reducing heating therein, comprising a wooden frame impregnated with moisture-excluding material, and glass insulator members thereon supporting said helix. 85

3. An inductor device comprising a coiled copper ribbon, glass insulating supporting members therefor having high heat-resisting properties, high physical strength and low dielectric loss properties, and a gum-treated wooden frame for supporting said insulating members. 90

4. An inductor device comprising a coiled copper ribbon, supporting members therefor comprising glass insulating members having high heat-resisting properties, high physical strength and low dielectric loss properties, a gum-treated wooden frame for supporting said insulating members, a portion of said frame comprising tensioning screws adapted to stretch said ribbon. 95

5. An inductor device comprising a gum-treated wooden frame, a plurality of rectangular glass insulator members carried thereby and a coiled copper ribbon positioned thereon, said insulator members having one surface slightly curved, edges adjacent thereto being rounded off, and spacing projections thereon. 105

6. An inductor device comprising a gum-treated wooden frame, a plurality of rectangular glass insulator members carried thereby and a coiled copper ribbon positioned thereon, said insulator members having one surface slightly curved, edges adjacent thereto rounded off, and spacing projections thereon, the width of said projections being slightly less than the distance between adjacent turns of said coiled ribbon and the space between said projections being slightly greater than the width of said ribbon. 115

7. An inductor device comprising a frame having longitudinally extending mechanically strong members near the exterior thereof and glass insulating members supported throughout their length by said mechanically strong members and a coil wound upon the exterior faces of said glass members. 125

8. An inductor device comprising a frame having longitudinally extending mechanically strong members near the exterior thereof and glass insulating members supported throughout their length by said mechanically strong members, a coil wound upon the exterior faces of said glass members and means for moving at least one of said longitudinally extending members radially to tension said coil.
9. In electrical apparatus, a helical coil, and a supporting cage comprising supporting elements and disposed longitudinally of the coil, said elements being identical and being identically notched to receive and separately support the convolutions of the coil and means for holding said supporting elements in spaced relationship about the circumference of said coil and axially offset in progressive relationship to each other so
- that their coil notches will conform to the pitch of the windings of said coil.
10. In electrical apparatus, a helical coil, and a supporting cage comprising substantially identical supporting elements disposed longitudinally of the coil, said elements being substantially identically notched to receive and separately support the convolutions of the coil, and means for holding said supporting elements in spaced relationship about the circumference of said coil and axially offset in progressive relationship to one another, the sum total of such axial offsets being equal to the space between the convolutions of said coil.

In testimony whereof, I have hereunto subscribed my name this 21st day of January, 1925.

FRANK CONRAD.
